UNITED STATES PATENT OFFICE.

WILHELM MAYER, OF ESSEN-ON-THE-RUHR, GERMANY, ASSIGNOR TO
FRIED. KRUPP AKTIENGESELLSCHAFT, OF ESSEN-ON-THE-RUHR, GERMANY.

AMMUNITION-VEHICLE.

No. 857,246.

Specification of Letters Patent.

Patented June 18, 1907.

Application filed June 18, 1906. Serial No. 322,320.

To all whom it may concern:

Be it known that I, WILHELM MAYER, a subject of the Emperor of Germany, and a resident of Essen-on-the-Ruhr, Rüttenscheid, Germany, have invented certain new and useful Improvements in Ammunition-Vehicles, of which the following is a specification.

The present invention relates to ammunition vehicles and in particular, limbers and rear ammunition wagons in which the ammunition is arranged vertically and one piece separated from the other, the object of the invention being to construct the box of such vehicles in such a manner that the vehicle becomes very strong and at the same time light and compact.

In the accompanying drawing, the invention is by the way of example shown applied to a limber.

Figure 1 is a rear view of the limber, partly in section; Fig. 2 is a section on line 2—2, Fig. 1, looking from above; Fig. 3 is a side view of the limber, partly in section on line 3—3, Fig. 1, and Fig. 4 shows a perspective of the bottom of the limber box.

The limber box is provided with a lid B and is divided into three compartments by means of two vertical partitions C into which are stamped bearings c' (Figs. 1 and 2) for the wheel-axle H, the two outer compartments being adapted to contain cartridges.

In the upper part of the two outer compartments are disposed horizontal partitions E (Figs. 1 and 3), in which are stamped seats e', one for each cartridge. In the sheet-metal bottom D of the wagon box are stamped a corresponding number of seats d⁵ (see also Fig. 4) which taper downwardly to fit the point of the projectiles, two caps F being secured to the bottom serve as protection for the projectile points which project downwardly from the seats d⁵.

The sheet-metal bottom D (Fig. 4) is provided with vertical flanges d' and d² which are formed by bending upwardly the edges of the bottom. The flanges d' and d² lie against the outer faces of the vertical walls

A, A', A² and A³ of the limber box and are riveted to said walls. In the flanges d' of the bottom sheet are stamped rectangular bearings d³ which project through corresponding perforations in the walls A², A³, of the limber box (see in particular Fig. 2). The pole G which is provided with the limber hook g' rests in the bearings d³, and is secured in position by means of rectangular frames J which are secured to the flanges d' and to the pole G.

In the flanges d² of the sheet metal bottom D are stamped cylindrical bearings d⁴ which project through perforations in the side walls A and A' (see in particular Fig. 1, left portion). The bearing faces of each of the bearings d⁴ are increased by means of a ring K secured to the flange d². The bearings d⁴ and the rings, K together with the above-mentioned bearings c of the partitions C receive the wheel axle H, which is held from rotation and axial displacement by means of bolts L which pass through the axle and the bearings c'.

The invention is equally useful for rear ammunition wagons, in which case the bottom of the wagon box must be provided with flanges which correspond to the flanges d' and which receive the draw-beam.

Having described my invention what I claim as new is:

1. An ammunition vehicle having a box provided with a bottom having side members with bearings for the wheel-axle.

2. An ammunition vehicle having a box provided with a bottom having side members with bearings for the pole.

3. In a device of the character described, a box bottom made from a single piece of metal and having upwardly bent flanges provided with bearings for the purpose set forth.

4. In a device of the character described, a box bottom made from a single piece of metal having upwardly bent flanges throughout its circumference; each of said flanges being provided with a bearing stamped therein.

5. In a device of the character described, a

box bottom made from a single piece of sheet metal; the bottom having its four edges bent to provide vertical flanges, and each flange being provided with a bearing.

5 6. An ammunition vehicle having a box provided with a bottom with seats for the projectiles and having a pair of side members provided with bearings for the wheel

axle and a second pair of side members provided with bearings for the pole.

The foregoing specification signed at Düsseldorf, this third day of May, 1906.

WILHELM MAYER.

In presence of—

WILLIAM ESENWEIN,
ALFR. FOHLMAYER.
